(57) **CLAIM**

The ornamental design for a hopper adapter, as shown and
described.

DESCRIPTION

FIG. 1 is a front perspective view of a hopper of the hopper
adapter according to a first embodiment of the present
invention;

FIG. 2 is a rear perspective view of the hopper of FIG. 1;
FIG. 3 is a left side elevation view of the hopper of FIG. 1;
FIG. 4 is a right side elevation view of the hopper of FIG.
1;

FIG. 5 is a front elevation view of the hopper of FIG. 1;
FIG. 6 is a rear elevation view of the hopper of FIG. 1;
FIG. 7 is a top plan view of the hopper of FIG. 1;
FIG. 8 is a bottom plan view of the hopper of FIG. 1;
FIG. 9 is a front perspective view of an adapter of the hopper
adapter according to a second embodiment of the present
invention;

FIG. 10 is a rear perspective view of the adapter of FIG. 9;
FIG. 11 is a left side elevation view of the adapter of FIG.
9;

FIG. 12 is a right side elevation view of the adapter of FIG.
9;

FIG. 13 is a front elevation view of the adapter of FIG. 9;
FIG. 14 is a rear elevation view of the adapter of FIG. 9;
FIG. 15 is a top plan view of the adapter of FIG. 9;
FIG. 16 is a bottom plan view of the adapter of FIG. 9;
FIG. 17 is a front perspective view of the hopper adapter
according to a third embodiment of the present invention;
FIG. 18 is a rear perspective view of the hopper adapter of
FIG. 17;

FIG. 19 is a left side elevation view of the hopper adapter of
FIG. 17;

FIG. 20 is a right side elevation view of the hopper adapter
of FIG. 17;

FIG. 21 is a front elevation view of the hopper adapter of
FIG. 17;

(Continued)

FIG. 22 is a rear elevation view of the hopper adapter of FIG. 17;
 FIG. 23 is a top plan view of the hopper adapter of FIG. 17;
 FIG. 24 is a bottom plan view of the hopper adapter of FIG. 17;
 FIG. 25 is front perspective view of the hopper adapter of FIG. 17 with the hopper exploded from the adapter; and,
 FIG. 26 is a rear perspective view of the hopper adapter of FIG. 17 with the hopper exploded from the adapter.
 The broken lines in the drawings depict portions of the hopper adapter that are not included in the claimed design.
